UNITED STATES PATENT OFFICE.

PHILIPP HAKE, OF HOBOKEN, NEW JERSEY.

DESIGN FOR A SOUVENIR BOOKLET.

SPECIFICATION forming part of Design No. 30,132, dated February 7, 1899.

Application filed January 11, 1899. Serial No. 701,885. Term of patent 7 years.

To all whom it may concern:

Be it known that I, PHILIPP HAKE, a citizen of the United States, and a resident of Hoboken, in the county of Hudson and State of New Jersey, have invented and produced a new and original Design for Souvenir Booklets, of which the following is a specification, reference being had to the accompanying drawing, forming a part thereof.

10 The drawing is a perspective view of a souvenir booklet, showing my new design.

As shown in the drawing, the leading or material feature of my design consists in such an article provided with a cord or append-

age, at the end of which is a ring surrounding 15 a diminutive roll. The appearance of the whole is that of a souvenir booklet, to the binding-cord of which is attached a diminutive facsimile of a diploma.

Having thus described my invention, the 20 following is what I claim as new therein and desire to secure by Letters Patent:

The design for a souvenir booklet; substantially as herein shown and described.

PHILIPP HAKE.
